TABLE

Frank Jacoby, East Orange, N. J.

Application May 25, 1955, Serial No. 36,204

Term of patent 3½ years

(Cl. D33—14)

Fig. 1

Fig. 1 is a perspective view of the table embodying my new design, looking from above.

Fig. 2 is a perspective view looking up from the bottom of the table.

Fig. 3 is a side elevational view of the table with the removable tray element in a different position from that shown in Figs. 1 and 2.

I claim:

The ornamental design for a table, as shown and described.
